ABSTRACT

Apparatus and method for forming deckle-free windows or openings in molded fiber products such as cartons, trays and the like, said apparatus comprising an air distributor manifold box with jet tube means whereby a blast of air may be directed against a block-out patch to lift deckle therefrom. The manifold box being movable to a discharge position and in contact with switch means which is operable to open a solenoid valve in fluid conduit means which connects said manifold box to an air accumulator tank. The operation of said apparatus providing the said method of removing deckle from the surface of block-out patches disposed on forming molds to form windows. The method of removing deckle from the surface of block-out patches by an air jet and pressing the up-lifted deckle into surrounding fiber portions to reinforce said surrounding portions.

**APPARATUS AND METHOD FOR FORMING
MOLDED FIBER PRODUCTS WITH DECKLE-FREE
WINDOWS**

BACKGROUND OF THE INVENTION 1. Field of the
Invention

The field of the invention is believed to encompass art found in Class 162, subclasses 227 and 286.

2. Description of the Prior Art

In the production of molded fiber products it is frequently desirable to form one or more apertures or windows therein, in particular in cartons or trays. The windows are formed by providing the forming molds with non-porous block-out patches or blocks. Concomitant with the use of block-out patches there is a build-up of undesirable fiber, known as deckle, around the edge of the windows. The removal of this undesirable fiber or deckle has been approached in the past, for example, by the application of water sprayed in the area to remove the deckle. The use of water spray to remove deckle has not been altogether satisfactory in that:

- A. stray fibers frequently remain around the edge of the windows,
- B. thickness of pulp formation in the window area may be adversely thinned out,
- C. pulp furnish in machine vat may be diluted, and
- D. manufacturing time is undesirably extended.

Other approaches for removing deckle include the use of air as disclosed in U.S. Pat. No. 2,923,654 to Comstock. It is noted that Comstock uses air in the vacuum forming die to remove deckle. The specific approach of Comstock complicates the die construction, die changing on the machine, and machine construction. Its practical use is for a very small area on a special purpose machine.

SUMMARY OF THE INVENTION

The present invention relates to improvements in an apparatus and a process for use in forming molded fiber products with windows therein. In particular, it is an object of this invention to provide an apparatus and method for forming molded fiber products with deckle-free openings or windows therein having edges with clean lines.

It is also an object of this invention to form a molded fiber product with windows therein having reinforced edges there around.

It is additionally an object of this invention to provide an apparatus and method for increasing the speed of manufacturing deckle-free windows in molded fiber products.

BRIEF DESCRIPTION OF THE DRAWINGS

FIG. 1 is a side elevation of the apparatus according to the present invention shown in use in conjunction with a molded fiber product molding machine;

FIG. 2 is a fragmentary view looking at the top of the forming mold just after pulp has been applied thereto;

FIG. 3 is a sectional view taken along line 3 — 3 in FIG. 2;

FIG. 4 is a view similar to FIG. 3 showing portions of jet tubes rotated 90° from the position in FIG. 1 for convenience;

FIG. 5 is a view similar to FIG. 4 showing a fragmentary portion of a pressing mold applied against the uplifted deckle; and

FIG. 6 is a fragmentary top plan view of a molded fiber product preform with deckle-free windows.

**DETAILED DESCRIPTION OF THE APPARATUS
ACCORDING TO THIS INVENTION**

Referring now particularly to FIG. 1, the apparatus according to the present invention is shown in use in conjunction with a rotating molded fiber product molding machine 10. The molding machine 10 comprises a 10 rotating wheel 12 which carries a plurality of forming molds 14, 14', etc. Each forming mold as shown is provided with a plurality of generally flat, non-porous block-out patches 15 for the formation of windows. As shown, the rotating wheel 12 continuously moves each 15 forming mold into a vat V of pulp slurry and thereafter adjacent an air distributor manifold box 20, below a pressing mold 16 and finally to a conveying belt 18 upon which preforms may be taken to a drying oven, for example.

20 The apparatus according to the present invention comprises the air distributor manifold box 20 which is provided with a plurality of jet outlet tubes 22 on one face thereof and a flexible hose 30 connected to the opposite face thereof. As shown in FIG. 1, air distributor manifold box 20 is fixedly connected to support link 24 for pivotal movement about pin 26. A microswitch mechanism 28 is fixedly disposed on the molding machine side of the support link 24. Flexible hose 30 is connected to a high pressure air accumulator tank 34. A solenoid operated valve 32 is disposed in the circuit of the flexible hose 30 between air distributor manifold box 20 and high pressure air accumulator tank 34. Upon movement of support link 24 from the phantom position to the solid position and into contact with microswitch 28, which is electrically connected to the solenoid of valve 32, the valve 32 will be opened to allow a burst of air to tank 34, through hose 30, into box 20 and out tubes 22.

40 On the upstream side of accumulator tank 34 compressed air is supplied thereto by way of pipe 36 in which there is provided an air pressure regulator valve 38. Air, for example, may be supplied in pipe 36 at 80 lbs. p.s.i. It is important that the diameter of pipe 36 be substantially smaller than that of discharge hose 30, so that the high pressure air is quickly dissipated to allow retraction of the air jet tubes without delamination of pulp in the area of the windows that are formed. In this connection pipe 36 might conveniently have a diameter of three-eighths inch compared to a three-fourths inch diameter for hose 30. It is also noted that air tank 34 may be provided with an air pressure gauge 40 to determine the pressure therein.

**METHOD AND OPERATION OF THE APPARATUS
TO FORM DECKLE-FREE WINDOWS**

55 In conjunction with the operation of the present invention the molding wheel 12 of molding machine 10 is rotated in the counter-clockwise direction as shown in FIG. 1 whereby each of the forming molds 14 are immersed in the fiber Vat V and coated with a pulp slurry. As the forming mold 14 emerges from the pulp vat the forming mold 14 will be covered with a pulp slurry 19. The non-porous block-out patches 15 on the mold 14 will have its edges surrounded by deckle 21. As clearly seen in FIG. 3 forming mold 14 is lined with a screening wire 17 upon which a plurality of spaced apart non-porous block-out patches 15 are disposed to form win-

dows in the molded product and deckle portions 21 are superimposed over the edges of the patches 15.

As the forming mold 14 moves to a generally vertical position as shown in FIG. 1 support link 24 is moved from the position shown in phantom to the solid line position in which air distributor manifold box 20 extends generally parallel to mold 14 and at which time support link 24 strikes microswitch mechanism 28 which opens solenoid operated valve 32 to allow a burst of air from accumulator tank 34 to pass through flexible hose 30 into air distributor box 20 and discharge through jet tubes 22 and against block-out patches 15. Each jet tube 22 is directed against the center of a patch 15 whereby a blast of air A sweeps across the face of each patch 15 to lift the deckle 21 off the patch and into upstanding position as shown in FIG. 4.

After the deckle 21 around each patch 15 is blasted into the upstanding position support link 24 is backed away to the phantom position shown in FIG. 1 and out of engagement with microswitch 28 whereby the solenoid operated valve 32 closes to permit build-up of air pressure in accumulator tank 34 for the next cycle. At the same time mold 14 continues in the counter-clockwise direction to a position beneath a pressure mold 16, such as a wet press head, for example, which is lowered in mating relationship with forming mold 14 and thereby compressing the upstanding deckle 21 against the pulp portions 19 as shown in FIG. 5.

Upon this engagement of molds 14 and 16, the fiber product preform 23 is formed with deckle-free windows 25 having clean smooth lines and surrounding portions 19 with reinforced pressed-together portions 21 surrounding the windows as illustrated in FIG. 6.

It will be obvious to those skilled in the art that various changes may be made without departing from the scope of the invention and the invention is not to be considered limited to what is shown in the drawings and described in the specification.

I claim:

1. Apparatus for use in forming deckle-free windows in molded fiber products comprising in combination a movable mold carrying member and an air distributor manifold box with jet outlet means on one face thereof and conduit means connected thereto whereby high pressure air may be introduced into said manifold box for discharge through said jet outlet means, said conduit means being connected to a high pressure air accumulator and including valve means controlling the flow of air from said accumulator, through said conduit means and to said manifold box, said manifold box being provided with movable support means whereby said manifold box may be moved to and from a discharging position to which one of a plurality of movable forming molds on said movable mold carrying

member is moved into registration therewith and against which high pressure air from said jet outlet means may be directed to thereby blast deckle off the surface on which it is deposited.

5 2. The apparatus as recited in claim 1 wherein said conduit means is in the form of a flexible hose and thereby facilitates free movement of said manifold box.

10 3. The apparatus as recited in claim 2 wherein actuating means is disposed in the path of movement of said movable support means adjacent the discharging position of said manifold box, said actuating means being operably connected to said valve means to open it when said manifold box is in the discharging position.

15 4. The apparatus as recited in claim 3 wherein said actuating means is in the form of a microswitch and is connected to said valve means by solenoid means operable to selectively open and close said valve means depending upon whether said manifold box is in the discharging position or not.

20 5. The apparatus as recited in claim 4 wherein said movable support means comprises a connecting link element pivotally connected to a fixed base.

25 6. The apparatus as recited in claim 5 wherein said high pressure air accumulator is connected to an air supply source by pipe means having a diameter substantially smaller than the diameter of said conduit means.

30 7. The apparatus as recited in claim 6 wherein said jet outlet means comprises a single jet tube for application of air against deckle of each window to be formed.

35 8. The apparatus as recited in claim 6 wherein said jet means comprises at least two jet tubes for application of air against deckle of at least two windows to be formed.

40 9. Apparatus for use in forming deckle-free windows in molded fiber products comprising an air distributor manifold box with jet outlet means on one face thereof and conduit means connected thereto whereby high pressure air may be introduced into said manifold box for discharge through said jet outlet means, said conduit means being connected to a high pressure air accumulator and including valve means controlling the flow of air from said accumulator, through said conduit means and to said manifold box, said manifold box being provided with movable support means whereby said manifold box may be moved to and from a discharging position wherein said movable support means comes into contact with and cooperates with actuating means disposed in its path to effect discharge of air through said jet outlet means, said actuating means being operably connected to said valve means for opening same.
